(Model.)

W. S. SMOOT.

Magazine Fire Arm.

No. 230,670.

Patented Aug. 3, 1880.

UNITED STATES PATENT OFFICE.

WILLIAM S. SMOOT, OF ILION, NEW YORK.

MAGAZINE FIRE-ARM.

SPECIFICATION forming part of Letters Patent No. 230,670, dated August 3, 1880.

Application filed May 20, 1880. (Model.)

To all whom it may concern:

Be it known that I, WILLIAM S. SMOOT, of Ilion, in the county of Herkimer and State of New York, have invented certain Improvements in Magazine-Guns, of which the following is a specification.

My present invention relates to certain improvements upon the magazine-gun for which a patent was granted to John W. Keene, ⁵ March 20, 1877, No. 188,468; and the invention relates to the mechanism which regulates or controls the feeding of the cartridges from the magazine to the chamber of the gun, as hereinafter more fully set forth.

¹⁰ Figures 1 and 2 are side elevations of that portion of the arm which contains the breech mechanism; Fig. 3, a vertical longitudinal section of the same. Figs. 4 and 5 are transverse vertical sections on the line *x x* of Fig. 1; Fig. 6, a sectional view taken on the line *y y* of Fig. 4; Fig. 7, a perspective view of the escapement detached; and Figs. 8 and 9 represent a modification of the stop for shutting off the flow of cartridges from the magazine. ¹⁵

²⁰ In the drawings, A indicates the frame or receiver, B the breech-bolt, and C the carrier, the general arrangement of these parts being the same as in the patent hereinbefore mentioned.

²⁵ The carrier C has a spring, D, arranged to press against its arm *m*, as shown in Fig. 3, for the purpose of controlling or holding it down after the breech is closed, the carrier being operated in both directions positively by the movement of the sliding breech-bolt B.

³⁰ The escapement, which controls the escape of the cartridges from the magazine F onto the carrier C, is shown detached in Fig. 7, and is provided with the two lips *a* and *b*, the same as in the patent referred to; but instead of having a spiral spring under its lower end to force it upward it is operated by a positive motion in both directions, as follows: A spring-plate, G, is pivoted by a pin, *c*, at its front end to the side of the receiver A, and held in place by a screw, H, passing through a slot, *g*, as shown in Figs. 1 and 2, the screw serving to regulate the tension or pressure of the spring-plate G. This spring-plate G rests between two shoulders, *h*, on the outer face of the escapement E, so that as it moves up and down it carries the escapement with it. At its rear

end the plate G is provided with a pin, *d*, which projects inwardly through a slot, *e*, in the wall of the receiver A, and engages in a notch, *t*, cut in the side of the carrier C, as shown in Fig. 3, by which means, as the carrier is elevated by the bolt B, the rear end of the plate G is raised, and it in turn elevates the escapement. ⁵⁵

It will be observed that the plate G is provided near its front end with two laterally-projecting arms, *f*, which bear upon the escapement near its upper and lower ends, as ⁶⁵ shown in Figs. 1 and 2; and as these arms also act as springs, the result is that the escapement E is permitted to be moved outward or sidewise at either end whenever force is applied to it for that purpose. ⁷⁰

As shown in Figs. 4 and 5, the front end of the bolt B is cut away slightly in such a manner as to form a shoulder, *k*, which is so located that when the bolt B is turned from the position shown in Fig. 5 to the position shown ⁷⁵ in Fig. 4 to unlock it the shoulder *k* engages or strikes upon the upper end of the escapement E, and as the bolt is turned shoves the escapement down, the escapement E, by its shoulder *k*, at the same time throwing down ⁸⁰ the rear end of the spring-plate G to the position shown in Fig. 2, the carrier C at such time being down, and therefore not interfering with the movement of the plate G.

The operation of the parts would then be as ⁸⁵ follows: Supposing the bolt B to be withdrawn, as represented in Fig. 3, the carrier C would be elevated, thereby raising the cartridge that would be upon it, (and which is shown in dotted lines,) so that it would enter ⁹⁰ the chamber of the barrel. As the bolt is shoved forward the cartridge would be pushed into the chamber, the carrier at the same time being forced down, and as the front end of the bolt comes in contact with the beveled inner face of the escapement the upper end ⁹⁵ of the latter would be shoved outward to the position shown in Fig. 4, the lip *b* at its lower end then serving to hold the cartridge K, as shown in Fig. 3. As the bolt B is turned to ¹⁰⁰ lock it fast, as shown in Fig. 5, the cut-away portion *J* permits the upper end of the escapement E to swing inward, as shown in said Fig. 5, so that as the bolt is turned to unlock it the shoulder *k* of the bolt will bear upon ¹⁰⁵ the upper end of the escapement E, thereby

shoving it down, and by depressing the lip *b* permit the cartridge resting against said lip to escape onto the carrier *C*, the next cartridge in the magazine at the same time coming 5 to a rest against the lip *a*. This same movement, as previously explained, throws down the rear end of the spring-plate *G*, so that as the carrier is again thrown up by the bolt *B* the plate is carried up with it, thereby also 10 raising the escapement, which permits the cartridge to escape from the lip *a* and come to rest against the lip *b*.

It will therefore be seen that, no matter how 15 many times the bolt *B* may be locked and unlocked, or even partially withdrawn, but a single cartridge can escape from the magazine, whereas in the gun as represented in the patent before mentioned the escapement was so operated as to release a cartridge each time 20 the bolt was locked and unlocked, whereby a second cartridge was not unfrequently allowed to pass into the receiver when there was already one there; or, if the carrier was raised, the second cartridge would pass out of the 25 magazine underneath the carrier, thus preventing it from operating; or, if the bottom of the receiver was open, the cartridge that thus passed under the carrier would fall to the ground.

30 My improvement not only prevents this, but the escapement, being operated positively in both directions, is less liable to get out of order.

I have shown the carrier *C* held up by a 35 spring catch, *n*, locking over a pin, *p*, as represented in Fig. 3, the catch being released by the bolt *B* as the latter is shoved forward; but

I do not claim this device as my invention; and, so far as my improvements are concerned, 40 any equivalent device may be used for this purpose.

For the purpose of cutting off the flow of cartridges from the magazine a pivoted lever, *I*, may be used, as represented in Figs. 1 and 2, 45 it having a beveled point or nose, *i*, which enters a hole, *r*, in the escapement *E*, thus drawing its upper end outward, as represented in Fig. 4, so that the escapement will not be acted upon by the shoulder *k* of the bolt *B*. 50 While in this position the escapement remains stationary, and therefore prevents the escape of the cartridges from the magazine, in which case the gun can be used as a single-loader.

In Figs. 8 and 9 I have shown another plan 55 for cutting off the flow of the cartridges from the magazine, which may be substituted for the above. In this case the notch *t* in the side of the carrier *C* is made to extend entirely across the side of the carrier, as shown 60 in Fig. 8, and on the under side of the carrier I arrange a slide or button, *a*, in such a manner that it can be made to close the bottom or lower end of the notch or slot *t* or shoved back and leave the notch open, at will. When 65 then notch is thus left open it will be seen that the carrier *C* can play up and down freely without operating the plate *G*, and that con-

sequently the escapement *E* will remain stationary, the same as when the lever *I* is used.

Instead of the button or slide *a* any other 70 form of device may be used, it only being necessary to close or open the slot *t* to make it operate, as described.

It will be understood that the magazine will be loaded by inserting the cartridges into its 75 rear end through the receiver, although, of course, it may be arranged to be loaded at the opposite end if desired.

It will be observed that, in order to obtain room for the escapement *E*, the front portion 80 of the receiver extends some distance back of the end of the barrel, as shown in Fig. 3, and that the front end of the breech-bolt when closed enters this closed portion of the receiver a corresponding distance, and that consequently the head of the cartridge when fired is held between the rear end of the barrel and the front end of the bolt within this portion of the receiver, which thus entirely surrounds the head of the shell. If the head of the shell 90 should burst while thus held, as is liable to happen, the gas would be driven out backward around the bolt, thereby endangering the eyesight of the person using the arm; and to prevent this I make a hole, *v*, through the wall of 95 the receiver at a point opposite the head or flange of the shell, as shown in Fig. 3. As there is more or less space all around the flange of the shell, and the breech-bolt is made to fill the space in the receiver in rear of the 100 head of the shell, it follows that any escaping gas will readily pass out through the opening *v*, and thus all danger from that source is avoided.

Having thus described my invention, what 105 I claim is—

1. The combination of the escapement *E*, spring-plate *G*, provided with the pin *d*, carrier *C*, and bolt *B*, provided with the lip *k*, all arranged to operate substantially as described.

2. The detent *E*, arranged to slide to and fro vertically and have its upper end swing laterally, in combination with the spring-plate *G* and the lever *I*, all arranged to operate as 115 described, for cutting off the flow of cartridges from the magazine, as set forth.

3. In combination with the escapement *E*, the spring-plate *G*, provided with the arms *f*, arranged to operate substantially as described, whereby the escapement is allowed to move laterally as well as vertically, as set forth.

4. The combination of the reciprocating escapement *E*, operated positively in opposite 125 directions by means of the breech-bolt and the carrier, with spring *G*, arranged to retain the escapement in position vertically while allowing it to yield laterally in loading the magazine.

WILLIAM S. SMOOT.
